CLAIM

The ornamental design for a tube squeezer, as shown and described.

DESCRIPTION

A portion of the disclosure of this patent document contains material that is subject to copyright protection. The copyright owner has no objection to the facsimile reproduction of the patent document or the patent disclosure, as it appears in the U.S. Patent and Trademark Office patent files or records, but otherwise reserves all copyright rights whatsoever. The following notice applies to the disclosure provided herein and to the drawings that form a part of this document: Copyright 2021, Design Labs, Inc.; All Rights Reserved. FIG. 1 is a right angled view of an embodiment of a tube squeezer as disclosed herein;

FIG. 2 is a left angled view of an embodiment of the tube squeezer as disclosed herein;

FIG. 3 is a top view of an embodiment of the tube squeezer as disclosed herein;

FIG. 4 is a bottom view of an embodiment of the tube squeezer as disclosed herein;

FIG. 5 is a front view of an embodiment of the tube squeezer as disclosed herein;

FIG. 6 is a rear view of an embodiment of the tube squeezer as disclosed herein;

FIG. 7 is a left side view of an embodiment of the tube squeezer as disclosed herein; and,

FIG. 8 is a right side view of an embodiment of the tube squeezer as disclosed herein.

The broken lines show portions of the tube squeezer that form no part of the claimed design.

1 Claim, 5 Drawing Sheets
